WALL-MOUNTED POT LID HOLDER OR THE LIKE

Leslie W. Eade, Box 27, Hana, Maui, Hawaii 96713

Filed Aug. 14, 1972, Ser. No. 280,555

Term of patent 14 years

Int. Cl. D6—04

U.S. Cl. D6—114

FIG. 1 is a front elevational view of a wall-mounted pot lid holder showing my new design;

FIG. 2 is a side elevational view thereof;

FIG. 3 is a top plan view taken along arrow 3 of FIG. 1.

FIG. 4 is a bottom plan view taken along arrow 4 of FIG. 1.

FIG. 5 is a rear elevational view taken along the arrow 5 of FIG. 2.

FIG. 6 is a sectional view taken on the plane 6—6 of FIG. 5.

I claim:

The ornamental design for a wall-mounted pot lid holder or the like, substantially as shown.
